Attorney

UNITED STATES PATENT OFFICE.

CHARLES O. LEE, OF MODESTO, CALIFORNIA.

IRRIGATION-TILE.

1,350,229.

Specification of Letters Patent. Patented Aug. 17, 1920.

Application filed January 17, 1920. Serial No. 352,045.

To all whom it may concern:

Be it known that I, CHARLES O. LEE, a citizen of the United States, residing at Modesto, in the county of Stanislaus and State of California, have invented new and useful Improvements in Irrigation-Tiles, of which the following is a specification.

This invention relates to tiles for irrigation and drainage purposes and the principal object of the invention is to so construct the tile that some of the water flowing through the same may escape therefrom and thus irrigate the land.

Another object of the invention is to provide the tile with means for preventing the escaping water from washing the dirt from beneath the tile.

This invention also consists in certain other features of construction and in the combination and arrangement of the several parts, to be hereinafter fully described, illustrated in the accompanying drawings and specifically pointed out in the appended claims.

In describing my invention in detail, reference will be had to the accompanying drawings wherein like characters denote the like or corresponding parts throughout the several views, and in which:—

Figure 1 is a view of a tile constructed in accordance with my invention.

Fig. 2 is a cross section of this tile.

Fig. 3 is a cross section showing a modification.

Fig. 4 is a view of another modification.

In these views 1 indicates the tile which may be formed of any suitable material and is provided with the socket part 2 at one end for receiving the small end of the adjacent tile so that the tiles may be connected together. The bottom of the tile shown in Figs. 1 and 2 is formed with an inwardly extending wedge-shaped projection 3, said projection being formed by the converging walls 4.

These walls form an inverted V-shaped recess 5 on the under side of the tile and openings 6 are formed in the upper ends of said walls, said openings connecting the interior of the tile with the recess 5.

It will thus be seen that as the water flows through the tiles it will pass in two streams on each side of the projection and if enough water is passing through to fill the tile to a level above the projection some of this water will pass through the opening 6 into the V-shaped recess and thus moisten

the ground around the tile. This water will pass down the inclined walls of the projection and thus be absorbed by the ground and will not wash the dirt from under the tile. In this way the land will be irrigated under the surface, thus avoiding baking of the soil and washing as will take place when the water is applied on the surface of the land. In this way also the water is delivered to the roots of the plants so that it will be immediately taken up by them without requiring it to soak through the ground before reaching the roots as in surface irrigation.

In the modification shown in Fig. 3 the tile 1' is provided with a flat bottom 1" and the projection 3" is formed on this flat bottom.

In the modification shown in Fig. 4 the tile 1" is provided with two projections 3" instead of one. In other respects, however, these two modifications are similar to the form above described and operate in the same manner.

The water passing through the openings will adhere to the sides of the inclined walls and will be absorbed by the soil without washing the soil from under the tile. With my invention the soil can be easily and quickly irrigated with much less water and with better results than when a surface irrigation is used. The arrangement of walls and openings also prevent said openings from being clogged.

I may use my improved tiles with a system of ordinary tiles for sub-irrigation, using the ordinary tiles to conduct the water to the improved tiles which are placed adjacent the plants or trees which are to be irrigated. Instead of ordinary tiles I may use pipes for conducting the water to my improved tiles.

It is thought from the foregoing description that the advantages and novel features of my invention will be readily apparent.

I desire it to be understood that I may make changes in the construction and in the combination and arrangement of the several parts, provided that such changes fall within the scope of the appended claims.

What I claim is:—

1. A tile of the class described having an inwardly extending wedge-shaped projection formed by converging portions of its wall, said projection forming a recess between its walls and having openings in its

inner end which communicate with said recess.

2. A tile of the class described having portions of its lower walls converging inwardly to form a V-shaped recess in the exterior part of the tile and openings in the upper portions of said converging walls communicating with said recess.

3. A water conduit having a hollow interior projection extending upwardly from

its bottom portion and dividing the lower part of the conduit into independent channels, the outer part of said projection being open and its upper part having apertures therein for permitting the water in the conduit to pass through the projection when the channels overflow. 15

In testimony whereof I affix my signature.

CHARLES O. LEE.
